UNITED STATES PATENT OFFICE.

JAMES MIRREY, OF EAST BOLDON, ENGLAND, ASSIGNOR TO A. REYROLLE & COMPANY, LIMITED, OF HEBBURN-ON-TYNE, ENGLAND, A BRITISH COMPANY.

ELECTRIC SWITCH GEAR.

Application filed December 1, 1924. Serial No. 753,375.

To all whom it may concern:

Be it known that I, JAMES MIRREY, subject of the King of England, and residing at East Boldon, in the county of Durham, England, have invented certain new and useful Improvements in Electric Switch Gears, of which the following is a specification.

This invention relates to electric switch-gear and has particular reference to switch-gear used in connection with duplex busbar systems.

In such switchgear the oil-break or other switches are often arranged so that they can be racked or otherwise moved in and out in relation to the stationary part of the gear containing the busbars and removable plugs are provided serving when in position to connect a selected busbar to the switch and when removed, to isolate that busbar. In some cases mechanism has been provided whereby the insertion of the plug has operated an indicator and prevented the insertion of the plug for the other busbar.

In switchgear according to the present invention, instead of the indicating mechanism being operated by the insertion of the plug, means are provided whereby the mechanism can be set to indicate a selected position of the plug and also to prevent the insertion of the plug in any other than such selected and indicated position. The insertion of the plug in the proper position locks the indicating mechanism and its setting lever or other operating mechanism.

The setting lever and indicating and locking mechanism are on the movable or "draw-out" portion of the switchgear and preferably there is provided on the fixed or busbar portion one or more switches controlling auxiliary circuits, such switches being operated by the setting lever in accordance with its position when the movable portion of the gear is moved in or out. For instance there may be two such auxiliary circuits and switches, one for synchronizing or like purpose and the other for giving a remote indication of the position of the plug say by means of a lamp, semaphore or other signal. Conveniently the setting lever is connected to the indicating and locking mechanism through a spring or like yielding coupling interposed at some suitable place to prevent the possibility of damage through rough handling.

In the accompanying drawings, Figure 1 is a diagrammatic view showing the essential features of the invention.

Figures 2 and 3 are plan views of parts of the indicating and setting mechanism in two positions other than that shown in Figure 1.

Figures 4 and 5 are sectional elevations showing the sockets for the removable plug and the adjacent mechanism in positions corresponding to Figures 2 and 3 respectively.

Figure 6 is an elevation partly in section showing the invention as applied to a known construction of metal-clad switchgear,

Figure 7 is a vertical section of the setting and indicating mechanism of Figure 6 drawn to a larger scale, and

Figure 8 is a cross-sectional plan on the line 8-8 of Figure 7 drawn to a larger scale than that figure.

For convenience Figure 6 will first be referred to as illustrating a known type of switchgear to which the invention is applied. In this figure A is a portion of the fixed part of the gear and comprises socket connections at B and C to duplicate busbars and another socket connection at D say to a feeder. The movable or draw-out portion indicated as a whole by the letter E comprises a main oil-break switch in its tank F, a plug connection G cooperating with the socket connection D and socket connections H and J which, by means of a removable plug K can be made to cooperate with either of the busbar socket connections B or C. These parts are well known in themselves and it will be understood that the movable portion E can be racked in and out and that the position of the removable plug K determines which of the busbars is selected for service and joined to the main switch.

Further description of the parts of Figure 6 to which the present invention more particularly relates are given later on and reference is now made to the diagrammatic Figures 1 to 5.

In Figure 1 the two busbar sockets B and C, the two sockets H and J of the movable portion and the removable plug K correspond to the parts bearing similar letters in Figure 6.

The usual connection L between the two sockets H and J is made tubular and contains within it a rotatable metal shaft L'.

having transverse holes L^2 and L^3 formed in it at levels corresponding to the centre lines of the sockets H and J. The holes are at an angle so that when one (L^2) is in line with its socket H the other (L^3) is not in line with its socket J. The removable plug K is formed with a pin or projection K' which can enter the hole in the locking shaft L' when such hole is in alignment with the socket. Thus the plug K can only be inserted properly into the socket H or the socket J when the shaft L' is turned into the correct position. In the position shown in Figure 1 the shaft has been turned into such a position that the pin K' can enter the hole L^2 and the removable plug K is fully home in the socket H so that when the movable portion of the switchgear is racked in, connection will be made to the busbar socket B.

The shaft L' is provided with an extension L^4 preferably of insulating material, upon which is mounted an arm or bracket L^5 carrying an arc-shaped indicating plate M working in conjunction with a window or opening M' through which the indications on the plate M can be read. At the top of the shaft L' L⁴ is mounted a bell crank lever N one end of which is pivoted to a handle or operating lever O and the other end pivoted to a link O' parallel to the operating lever O and joined to it by another bell crank lever N' so that the lever O moves parallel to the link O'. Stops P and P' are provided to limit the movement of the operating lever O in each direction and round the upper part of the shaft L' L⁴ is a coiled spring R which tends to rotate the shaft into the position shown in Figures 2 and 4 where the indicating plate M occupies a central position in relation to the window M' and the shaft L' is in such a position that the removable plug cannot be inserted in either of the sockets H or J.

It will be seen that the ends of the springs R act upon a fixed block R' and upon an arm or projection R² fixed to the shaft and that in the position shown in Figure 1 the shaft has been rotated into one extreme position of the operating rod O, where, as previously mentioned, the hole L^2 in the shaft will allow the entrance of the pin K' on the removable plug K. In this position the indicating plate M would display through the window M' the words "Top plug in" or some equivalent description of the position of the removable plug.

Supposing the gear to be in this position and the movable portion to be racked in, the operating bar O will depress the handle S of a switch or switches S' and cause them to close the circuit or circuits which they control. Similarly if the shaft L' L⁴ be rotated so that the operating lever O lies against the stop P' the position of the parts

will be as shown in Figures 3 and 5, the pin K' of the removable plug K being allowed to enter the hole L^3 and the indicator M displaying through the window M' the words "Bottom plug in." When the mechanism is in this position the racking in of the movable portion of the switchgear will cause the operating lever O to depress the handle S² of the switch or switches S' and the circuits controlled by those switches will be closed. It will be seen that the handles S S² are spring-controlled so that the switch opens when the operating bar no longer depresses the handle. Further the arrangement is such that after the bar O has depressed the handle S or S² it can slide over it keeping it down but putting no further strain on the closed switch.

The removal of the plug K after the movable portion of the switch has been racked out will release the locking shaft L' and that member will be turned by the action of the spring R into the position shown in Figure 4 where neither of the holes L^2 or L^3 are in alignment with their sockets and consequently the plug K cannot be inserted in either the socket H or the socket J. The indicating plate M will in such circumstances be in its mid position as shown in Figure 2 and will display the words "No plug in" or their equivalent. The operating bar O will also be in its mid position where, if the movable portion of the gear were racked in, it would pass between the switch handles S and S² and not operate either of them. Obviously a third switch could be provided if desired to be operated by the bar O when in its mid position.

No circuits are shown in connection with the switches S and S' as the details of such circuits do not in themselves form part of the present invention. It will however be understood that, as previously mentioned, the circuits may give an indication of the condition of the gear at some remote point or may be circuits used for synchronising or like purposes.

The details of construction in Figures 1 to 5 are more or less diagrammatic in order to make the operation of the invention clear. Such details are in some instances varied in the construction shown in Figure 6 but where the parts are identical or similar they bear the same reference letters in Figure 6 as in Figure 1.

Certain modifications of construction are embodied in the form of switchgear shown in Figure 6 and these will now be described with particular reference to that figure and to Figures 7 and 8, in which latter figures they are drawn to larger scales.

It is preferred to provide a spring or like yielding connection between the operating or setting lever O and the locking shaft L' L⁴ and this detail is shown in the sec-

tional view forming Figure 7 and in the plan view forming Figure 8. In these figures the shaft L^4 terminates in a sleeve L^6 to which it is secured by a pin L^7 . This sleeve L^6 has secured to it an arm L^8 carrying the indicator plate M^2 . Into a guide socket in this sleeve L^6 the lower end of an auxiliary shaft L^9 fits loosely the upper end of this shaft L^9 being mechanically connected to the operating bar or setting lever O . Upon this auxiliary shaft L^9 are loosely mounted two bushes or sleeves T and T' encircled by a coiled spring U one end of which is secured to the upper sleeve T and the other to the lower sleeve T' . The sleeve T has a projection T^2 engaging with one side of a rib L^{10} on the arm L^8 , and the other sleeve T' has a projection T^3 engaging with the other side of the rib. The auxiliary shaft L^9 is provided with two pins engaging respectively with projecting faces on the sleeves or their flanges. One of these pins T^4 is shown in Figures 7 and 8 and the other pin T^5 is shown in dotted lines in Figure 7. The whole arrangement is such that partial rotary movement of the auxiliary shaft L^9 by the operating lever O will be transmitted through the spring U to the indicator M^2 and to the locking shaft $L' L^4$. The presence of the spring U however prevents damage to the gear if an attempt should be made to move the setting lever whilst the shaft L' is locked by the pin K' of the removable plug K .

The control of the auxiliary shaft L^9 is effected by a spring R^3 acting in a manner substantially the same as that in which the spring R of Figures 1, 2 and 3 operates. This spring R^3 acts upon a lug R^4 on a collar R^5 secured to the auxiliary shaft L^9 .

The above described constructions are given by way of example only and variations in details may be made without departing from the spirit of the invention. For instance the movement of the locking shaft L' although conveniently rotary need not necessarily be such. Any other movement having the effect of setting the indicator and bringing the holes for the pin K' on the removable plug K into and out of registration with the sockets may be used.

Further although it is convenient to make the movement of the lever O a parallel motion such is not necessarily the case so long as the end of the lever is moved so that it can conveniently operate the switches in its various positions.

Again the construction may be modified to suit switch gear in which it is required that when desired both plugs can be inserted at the same time. A modification of this kind may be made in the constructions described by making slots instead of the holes $L^2 L^3$ in the locking shaft and by so

disposing those holes relatively to the shaft 65 and the plug sockets H and J that at one position both plugs can be inserted whilst at other positions one or the other plug only can be inserted or neither plug can be inserted. In such a case the indicator will be 70 arranged to give the appropriate indication and the auxiliary switches likewise arranged to suit the various positions of the setting lever.

Although the switches are preferably 75 mounted on the fixed or busbar portion of the gear, it is not necessarily so and they may be mounted on the movable portion and be directly operated by the mechanism controlling the position of the locking shaft. In that case however the auxiliary circuits are preferably arranged so that they are only completed when the movable portion of the gear is racked in.

Although in the above description only 80 two busbars have been referred to it will be understood that the invention may be applied say to a three-phase duplex busbar system and that the setting and indicating mechanism described may be provided for each phase, the setting levers being linked together if desired.

What I claim as my invention and desire to secure by Letters Patent is:—

1. In electric switchgear of the draw-out type, the combination of a plurality of busbar sockets, a main switch, sockets connected to said main switch, a movable member having holes or slots at levels corresponding to the centre line of the sockets, a removable plug serving when inserted in one of the main switch sockets to connect it with one of the busbar sockets, a pin or projection on said removable plug adapted to enter the corresponding hole in said movable member and means for moving said member to allow the entrance of said pin or projection into the hole and for indicating the selected position of the plug.

2. In electric switch gear of the draw-out type the combination of a plurality of busbar sockets, a main switch, sockets connected to said main switch, a tubular member connecting said main switch sockets, a shaft rotatable in said tubular member and provided with holes or slots at levels corresponding to the centre lines of the sockets, a removable plug serving when inserted in one of the main switch sockets to connect it with one of the busbar sockets, a pin or projection on said removable plug adapted to enter the corresponding hole in the shaft and means for partially rotating the shaft and for indicating the selected position of the plug.

3. In electric switchgear of the draw-out type the combination of a plurality of busbar sockets, a main switch, sockets connected

to said main switch, a removable plug serving to connect a selected busbar socket to a main switch socket, mechanism which can be set to indicate the selected position of the plug
 5 and to prevent the insertion of the plug in any other than such position and auxiliary switches operated according to the position of said setting mechanism.

4. In electric switchgear of the draw-out
 10 type the combination of a plurality of busbar sockets, a main switch, sockets connected to said main switch, a tubular member connecting said main switch sockets, a shaft rotatable in said tubular member and provided with holes or slots at levels corresponding to the centre lines of the sockets, a removable plug serving when inserted in one of the main switch sockets to connect it with one of the busbar sockets, a pin or projection on said removable plug adapted to enter the corresponding hole in the shaft, a lever for partially rotating said shaft and auxiliary switches operated according to the position of said lever.
 15
 20
 25
 30
 35
5. In electric switchgear of the draw-out type the combination of a plurality of busbar sockets, a main switch, sockets connected to said main switch, a tubular member connecting said main switch sockets, a shaft rotatable in said tubular member and provided with holes or slots at levels corresponding to the centre lines of the sockets, a removable plug serving when inserted in one of the main switch sockets to connect it with one of the busbar sockets, a pin or projection on said removable plug adapted to enter the corresponding hole in the shaft, a lever for partially rotating said shaft and auxiliary switches operated according to the position of said lever.

yielding coupling or connection between the lever and the shaft.

6. In electric switchgear of the draw-out type the combination of a plurality of busbar sockets, a main switch, sockets connected to said main switch, a tubular member connecting said main switch sockets, a shaft rotatable in said tubular member and provided with holes or slots at levels corresponding to the centre lines of the sockets, a removable plug serving when inserted in one of the main switch sockets to connect it with one of the busbar sockets, a pin or projection on said removable plug adapted to enter the corresponding hole in the shaft, a lever for partially rotating said shaft, a yielding coupling or connection between the lever and the shaft and auxiliary switches operated according to the position of said lever.

7. In electric switch gear of the draw-out type, the combination of a plurality of busbar sockets, a main switch, sockets connected to said main switch, a movable member having an opening for each socket, but one of which may register with a socket at a time, a removable plug serving when inserted in one of the main switch sockets to connect it with one of the bus bar sockets, a projection on said removable plug adapted to enter an opening in said movable member and means for moving said member to allow the entrance of said projection in any selected hole.

In testimony whereof I have signed my name to this specification.

JAMES MIRREY.
